TIME MEASURING APPARATUS

Crawford E. Staples, Wilkinsburg, Pa., assignor to
The Union Switch & Signal Company, Swiss-
vale, Pa., a corporation of Pennsylvania

Original application March 13, 1935, Serial No.
10,869. Divided and this application December
4, 1936, Serial No. 114,230

7 Claims. (Cl. 161—1)

My invention relates to time measuring apparatus, and particularly to electrically operated time measuring apparatus.

A feature of my invention is the provision of novel and improved means to actuate a circuit controlling contact member in accordance with the lapsed time of an event, such as, for example, the time required for a railway train to operate over a stretch of track. Other features and advantage of my invention will appear as the specification progresses.

This application is a division of my application, Serial No. 10,869, filed March 13, 1935, for Apparatus for the control of highway crossing signals, now Patent No. 2,039,919, granted August 10, 1937.

I will describe one form of apparatus embodying my invention, and will then point out the novel features thereof in claims.

20 In the accompanying drawings, Fig. 1 is a view partly diagrammatic and partly in elevation of one form of apparatus that may be employed in carrying out the embodiment of my invention. Fig. 2 is a plan view partly diagrammatic of a portion of the apparatus of Fig. 1. Fig. 3 is a detail view of the biasing spring for the apparatus of Figs. 1 and 2. Figs. 4 and 5 are diagrams illustrating certain characteristics of the apparatus of Figs. 1, 2 and 3.

30 Similar reference characters refer to similar parts in each of the views.

Although a particular application of apparatus embodying my invention is here disclosed, it will be understood the invention is not limited to this one application and many places will suggest themselves where time measuring apparatus embodying my invention will be useful.

Referring to Fig. 1, the reference characters l and l^a designate the track rails of a stretch of railway track over which traffic normally moves in the direction indicated by an arrow and which stretch is intersected by a highway H . Two highway crossing signals S_1 and S_2 are located adjacent the intersection and are indicated on the drawings by symbols commonly used in the art to designate a flashing light highway crossing signal. As is common practice, these two signals are set for one to be plainly exhibited to highway traffic approaching the crossing in one direction and the other signal to be plainly exhibited to highway traffic approaching the crossing from the opposite direction.

As here shown, the track rails l and l^a are divided by the usual insulated rail joints to form 55 three track sections $R-S$, $S-T$ and $T-V$, which

sections are traversed successively in the order named by a train approaching the highway H when moving in the normal direction of traffic. Each track section is provided with a track circuit comprising a battery 3 connected across the track rails at one end of the section and a track relay designated by the reference character R plus an exponent corresponding to its location connected across the rails at the other end of the section. For the purpose of this description 10 I shall refer to the track section $R-S$ as a measuring section, section $S-T$ as an operating section, and the section $T-V$ as a positive operating section. As will appear hereinafter, the speed of a train as it traverses the measuring 15 section $R-S$ is measured, the highway signals S_1 and S_2 are set into operation in accordance with this measured speed after the train has entered the operating section $S-T$ and positive operation of the signals S_1 and S_2 occurs during 20 the time the train occupies the section $T-V$ irrespective of whether it is moving or not.

In order to more easily understand the apparatus embodying my invention I shall assume a maximum speed for all trains approaching the 25 highway H of 60 miles per hour. I shall also assume a time interval of 20 seconds exhibit of the highway signals before a slow moving train reaches the intersection and that this interval is uniformly increased as the speed becomes 30 greater until an exhibit of 30 seconds of the highway signals for a train traveling at the maximum speed of 60 miles per hour is provided. I shall further assume the measuring section $R-S$ to be 880 feet in length, that is, the section $R-S$ 35 is of such length that a train moving at the maximum speed of 60 miles per hour consumes approximately 10 seconds in advancing therethrough. The combined lengths of the operating section $S-T$ and the positive operating section 40 $T-V$ are substantially 2640 feet since a train traveling at the maximum speed of 60 miles per hour moves 2640 feet in 30 seconds and, as above stated, a 30 seconds' exhibit of the highway crossing signals before a train traveling at the maximum speed reaches the intersection is desired. The section $T-V$ is preferably just long enough, say 200 feet, that operation of the highway crossing signals with a train occupying the intersection whether it is moving or not is assured. It 45 follows that with the track arrangement here assumed the highway crossing signals S_1 and S_2 are set into operation for a train traveling at the maximum speed immediately upon the train entering the operating section $S-T$, but that for 50

55

a train having a lower speed the starting of the operation of the signals S_1 and S_2 is delayed after the train enters the operating section $S-T$, this delay being such that the period of operation 5 of the highway signals before a train reaches the intersection becomes proportionally less as the speed becomes lower until at a speed of 20 miles per hour the period of operation is only 20 seconds whereas at the maximum speed 10 the period of operation is 30 seconds. For speeds lower than 20 miles per hour the period of operation remains substantially constant at 20 seconds. It will be understood, of course, that my invention is not limited to the above-stated 15 values of speeds, lengths of track sections and operating intervals of the highway crossing signals, and such values may be selected best suited for the location at which the apparatus is installed.

20 The operation of the signals S_1 and S_2 is governed by an operating unit here shown as an oscillator or code transmitter designated as a whole by the reference character CT . This oscillator CT may take different forms but a preferred form 25 is that described and claimed in Letters Patent No. 1,858,876, granted May 17, 1932, to Paul N. Bossart, for Coding apparatus. It is deemed sufficient for the present application to give but a brief description of this oscillator CT . A magnetic field structure 5 has mounted between its 30 two poles P_1 and P_2 a spindle 8 on which an armature 6 is fixed so as to swing freely between the pole pieces. The armature 6 and the spindle 8 are normally biased to the position illustrated 35 in Fig. 1 by any convenient biasing means such as a coil spring not shown, and the armature 6 is adapted to be attracted toward the pole pieces of the field structure in response to a magnetic field created therein. As indicated schematically 40 by dotted lines, three cam members 9 , 10 and 11 are fixed on the spindle 8 . These cam members 9 , 10 and 11 are each effective when rotated with the spindle 8 in a manner to shortly appear, to 45 actuate a pair of circuit controlling contact fingers. A field winding 7 is mounted on the field structure 5 and is provided with a plurality of energizing circuits all of which include the pair of contact fingers actuated by the cam member 11 . When the relay R^S is deenergized and its 50 back contact 12 is closed, a circuit is completed which extends from the B terminal of any convenient source of current such as a battery, not shown, over wire 13 , back contact 12 of relay R^S , wire 14 , winding 7 , contact $15-16$ actuated by the cam 11 and thence to the opposite terminal C of the same source of current. In the 55 event the track relay R^T is shunted and its back contact 17 is closed, or if the track relay R^V is shunted and its back contact 18 is closed, a circuit extends from the B battery terminal over the back contact 17 of relay R^T , or over the back contact 18 of the relay R^V , wire 14 , winding 7 , contact $15-16$ and to the C battery terminal. It follows that as long as any one of the track 60 relays R^V , R^T and R^S is shunted, the field winding 7 is supplied with current, but that when all three of these relays are picked up the winding 7 is without current. With the winding 7 energized and a magnetic field created in the field structure 5 , the armature 6 is attracted toward the pole pieces and the spindle 8 is rotated in a counter-clockwise direction against the force of the bias. After a slight movement of the armature 6 in the counter-clockwise direction, the cam member 11 actuates the contact finger 15 out of engage- 70

ment with the contact finger 16 and the circuit connection therethrough is broken with the result that the field winding 7 is deenergized. The armature 6 rotates a little farther and then its movement is reversed due to the bias and it swings clockwise toward its normal position. The cam member 11 is now rotated back toward its normal position and the contact $15-16$ is again closed and the winding 7 is reenergized. Armature 6 swings clockwise slightly past its normal 10 position due to the inertia of its parts and it is then again rotated in a counterclockwise direction due to the influence of the magnetic field. Consequently, as long as any one of the track relays R^S , R^T or R^V is shunted and the field winding 7 is supplied with current, the armature 6 oscillates at its natural period, the period of oscillation being determined by the bias and the weight of the parts. Although the period of oscillation may be any convenient frequency, I 15 shall consider it to be 30 cycles per minute.

20 As stated above, the cam members 9 and 10 are fixed on the spindle 8 , and hence the cam members 9 and 10 are rotated in response to the operation of armature 6 . The cam member 9 is so shaped that when rotated counterclockwise the associated contact fingers 19 and 20 are forced apart to break engagement and open the circuit connection therethrough, but that when rotated in the clockwise direction within the limits of 30 the movement of the armature 6 , the contact fingers 19 and 20 remain in engagement to close the circuit connection therethrough. The cam member 10 is so shaped that when rotated clockwise the associated contact fingers 21 and 22 are forced apart to open the circuit connection therethrough but when rotated in the counterclockwise direction within the limits of the movement of the armature 6 , the contact fingers 21 and 22 remain in engagement. It follows that 35 as the armature 6 is rotated counterclockwise the contact $19-20$ is opened and as the armature 6 swings clockwise past its normal position the contact $21-22$ is opened, but that at all other times these two contacts are closed. 40

45 The contacts $19-20$ and $21-22$ govern the circuits for lighting the lamps of the highway crossing signals S_1 and S_2 . With positive current supplied to the wire 23 in a manner to subsequently appear, current flows thence through contact $19-20$ over wire 24 , lamp 25 of signal S_1 and to the negative terminal C of the source of current. Branching from the wire 24 the current flows over a circuit including wire 26 , lamp 27 of signal S_2 and to the negative terminal C of the current source. Current also flows from wire 23 through the contact $21-22$ and thence over wire 27 and the lamps 28 and 29 of signals S_1 and S_2 , respectively, in parallel and to the negative terminal C of the current source. It is to 50 be seen, therefore, that with positive current supplied to the wire 23 and the oscillator CT inactive, both lamps of each signal S_1 and S_2 are steadily illuminated, but that with the oscillator operated in the manner explained and the contacts $19-20$ and $21-22$ alternately opened and closed, the lamps 25 and 28 of signal S_1 and the lamps 26 and 29 of signal S_2 are alternately flashed, the rate at which the signals are flashed being substantially 30 times per minute since 55 the frequency of the oscillator CT is 30 cycles per minute.

60 The oscillator CT in addition to governing the operation of the highway crossing signals S_1 and S_2 in the manner just described, also actuates a 65

time measuring mechanism effective to determine the speed of the train approaching the highway H and by which mechanism the time of starting of the operation of the signals S₁ and S₂ before the train reaches the intersection is governed. I shall now describe this time measuring mechanism which is designated as a whole by the reference character TE. A worm 30 is rigidly mounted on the spindle 3 and rocks a lever 31 pivoted at 32 and on which lever a pawl 33 is pinned for engaging with a ratchet gear 34 with the result that the ratchet gear 34 is rotated clockwise as viewed in Fig. 1, in response to oscillations of the armature 5 of the oscillator CT. A latch 35 holds the ratchet gear 34 on the return stroke of the pawl 33. The ratchet gear 34 is keyed to a shaft 36 journaled at 37 and 38 (see Fig. 2). A gear 39 and a cam 40 are loosely mounted on the shaft 36 between the bearings 37 and 38, and between the gear 39 and the cam 40 a clutch member 41 and two springs 42 and 43 are provided. The clutch member 41 is secured to the shaft 36 by a feather key not shown, and hence, it rotates with the shaft 36 and may be moved along the shaft toward either the gear 39 or toward the cam 40. The forked end of a lever 44 pinned at 45 rides in a slot 46 of the clutch member 41. The lever 44 is biased upward as viewed in Fig. 2 by a spring 47 and is in magnetic relationship with an electromagnet 48, the arrangement being such that the magnet 48 when energized is effective to draw the lever 44 downward as viewed in Fig. 2 against the force of the spring 47. It is to be seen, therefore, that magnet 48 when energized is effective to move the clutch member 41 and spring 43 into frictional engagement with the cam 40 whereby the cam 40 is made to rotate clockwise in response to clockwise movement of the ratchet gear 34, but that magnet 48 when deenergized permits the spring 47 to draw the lever 44 upward and move the clutch member 41 out of engagement with the cam 40 and into engagement with the gear 39 through the spring 42 and that gear is rotated clockwise in response to clockwise movement of the ratchet gear 34. In other words, the cam 40 is rotated clockwise in response to operation of the oscillator CT and ratchet gear 34 when the clutch magnet 48 is energized but is left free to turn on the shaft 36 when the magnet 48 is deenergized. The cam 40 is provided with a counterweight 71 and is so proportioned that it is immediately restored to its normal position, that is, to the position illustrated in Fig. 1, whenever the clutch magnet 48 is deenergized.

The gear 39 meshes with a gear 49 keyed to a shaft 50 which is journaled at 51 and 52 and on which shaft is keyed a restoring cam 53. A stationary spring case 54 has contained therein a coiled spring 55 (see Fig. 3) which is secured to the shaft 50 as well as to the case 54. The spring 55 is effective to bias the shaft 50 in the clockwise direction. Consequently, when the gear 39 is coupled to the shaft 36 through the clutch member 41 and is rotated clockwise, the gear 49, shaft 50 and cam 53 are rotated counterclockwise against the force of the spring 55 except when the mutilated portion 70 of gear 49 is adjacent the gear 39. Furthermore, when the gear 39 is released from the shaft 36 the spring 55 is effective to rotate the shaft 50 and cam 53 clockwise

unless the cam 53 is restrained by other means in a manner to later appear.

The cams 40 and 53 are utilized to operate a circuit contact controlling member or element and here shown as an arm 56. The arm 56 is pivoted at 57 and is provided with cam followers 58 and 59 positioned to ride on the cams 40 and 53, respectively. A contact finger 60 is secured to the arm 56 by proper insulation and this contact finger 60 makes engagement with a stationary contact 61 when the arm 56 occupies the normal position, that is, the position illustrated by solid lines in Fig. 1, but breaks engagement with the contact 61 as soon as the arm 56 is rotated upward about its pivot 57. An armature 62 of suitable magnetic material and a second contact finger 63 are also secured to the arm 56, the contact finger 63 being properly insulated from the arm. An electromagnet 64 is located for magnetic relationship with the armature 62 when the arm 56 is rotated upward to a reverse position illustrated by the dotted lines in Fig. 1, and on the casing of the magnet 64 a stationary contact 65 is secured for making engagement with the contact finger 63 when the arm 56 is moved to its reverse position. The function of the magnet 64 and the contacts 60—61 and 63—65 will appear when the operation of the apparatus is described.

In describing the operation of the apparatus, I shall assume the track sections R—S, S—T and T—V are unoccupied and the respective track relays are picked up so that the oscillator CT is inactive, the magnet 48 is energized, and the lamps of the highway crossing signals S₁ and S₂ are all dark. Furthermore, I shall assume the cams 40 and 53 and the arm 56 occupy their normal positions, that is, the positions illustrated in the drawings. It is to be noted that in this normal position of the apparatus, the magnet 48 is supplied with current from the B terminal of the current source over front contact 66 of relay R^V, front contact 67 of relay R^T, wire 68, winding of the magnet 48 and to the opposite terminal C of the current source, and the magnet 48 is energized to attract the lever 44 and draw the clutch member 41 into engagement with the cam 40. A train approaching the highway H from the right and entering the measuring section R^S shunts the track relay R^S and its back contact 12 is closed with the result that current is supplied to the field winding 7 of the oscillator CT and the armature 6 is set into operation. Although the cam members 9 and 10 are operated to actuate the contacts 19—20 and 21—22 the lamps of the highway crossing signals S₁ and S₂ remain dark since the wire 23 is connected to a back contact 69 of the magnet 48 and that magnet is now energized and its back contact 69 is open. Operation of the oscillator CT at this time causes, however, the ratchet gear 34 to be rotated, and hence the cam 40 is moved clockwise since the magnet 48 is energized and the clutch member 41 is in frictional engagement with the cam 40. In the event this train I have assumed to be approaching the highway H is traveling at the maximum speed of 60 miles per hour, it consumes approximately 10 seconds in advancing through the measuring section R—S and entering the operating section S—T where it shunts the track relay R^T. The cam 40 is so shaped that its movement caused by the first 10 seconds of operation of the oscillator CT effects no upward movement of the arm 56 and, consequently, the contact 60—61 is still closed when the train enters the section S—T. That is to say, this portion of the surface of the cam 40

is an arc of a circle, the center of which is the center of shaft 36. The shunting of the track relay R^T and the closing of its back contact 17 continues the supply of current to the field winding 7 of the oscillator CT, with the result that the oscillator continues to operate as long as the train occupies the section S—T notwithstanding the fact the rear of the train may vacate the section R—S and the track relay R^S may be picked up. Since the magnet 48 is deenergized and its back contact 69 is closed when the track relay R^T is shunted, current is supplied to the signals S1 and S2 for illumination of their respective lamps. This circuit is traced from the B battery terminal over contact 60—61 operated by the arm 56, back contact 69 of magnet 48, wire 23, contacts 18—20 and 21—22 in parallel and thence to the lamps of the signals S1 and S2 as previously traced. Since the cams 9 and 10 are now alternately opening and closing the contacts 18—20 and 21—22, the two lamps of each of the signals S1 and S2 are alternately flashed to exhibit a flashing signal to the highway users. When this train advances and enters the section T—V and the track relay R^V is shunted, the field winding 7 of the oscillator CT is still supplied with current over the back contact 18 of the relay R^V and hence the signals S1 and S2 are flashed until such time as the rear of the train has advanced to the left of the highway H and vacated the section T—V, since the magnet 48 is deenergized with relay R^V released. Inasmuch as the combined lengths of the sections S—T and T—V are equal to 2640 feet, there is a 30 seconds' operation of the highway signals before the train traveling at the maximum speed of 60 miles per hour reaches the intersection. During the entire time the train occupies the sections S—T and T—V the ratchet gear 34 is rotated clockwise and the gear 39 is driven clockwise since the magnet 48 is now deenergized and the clutch member 41 is forced into frictional engagement with the gear 39 due to the spring 47. Rotation of the gear 39 causes no rotation of the gear 49 at this time, however, since the teeth of the portion 70 of the gear 49 are cut away. The spring 55 secured to the shaft 50 is so proportioned and adjusted that it is effective to hold the shaft 50, gear 49 and cam 53 in the normal position where the cam 53 is in engagement with the cam follower 58 of the arm 56, but it is not of sufficient force to rotate the cam 53 against the weight of the arm 56 at such time as the gear 39 is released and free to turn on the shaft 36. Consequently, for a train traveling at the maximum speed of 60 miles per hour the cam 40 is rotated clockwise during the time the train is advancing through the measuring section but with no movement of the arm 56, the highway crossing signals are flashed for 30 seconds prior to the arrival of the train at the intersection, and they continue to flash until the rear end of the train has passed beyond the highway and cleared the section T—V. The cam 40 is restored to its normal position immediately upon the train entering the section S—T due to the influence of the counterweight 71, since the magnet 48 is now deenergized.

In the event a train approaches the highway H travelling at a speed less than the maximum speed, an operating interval different from the 30 seconds' interval of operation obtained for the maximum speed is effected, the interval decreasing from 30 seconds in proportion to the decrease in the speed. I shall now assume a train traveling at 40 miles per hour approaches the highway.

The relay R^S is shunted and the oscillator CT is set into operation as this train enters the measuring section R—S the same as explained for the train traveling 60 miles per hour. The train traveling 40 miles per hour consumes approximately 15 seconds in advancing through the section R—S and entering the section S—T. During this 15 seconds the cam 40 is rotated clockwise since the magnet 48 is energized, and during the first 10 seconds the cam 40 is rotated there is no upward movement of the arm 56 due to the circular surface of the cam as explained before, but the surface of the cam 40 is so shaped that after the first 10 seconds' movement thereof the arm 56 is raised at a variable rate. In other words, the cam 40 is so shaped that from each one second operation of the cam after the first 10 seconds' period the arm 56 is caused to move a different angular movement about its pivot 57, this angular movement progressively increasing for a limited time. The result of this upward movement of the arm 56 is to cause the contact 60 to move away from engagement with the stationary contact 61. During the upward movement of the arm 56 the spring 55 is effective to rotate the shaft 50 and cam 53 clockwise with the result that the cam 53 follows along after the arm 56 maintains its engagement with the cam follower 58. The gear 49 on the shaft 50 is now brought into mesh with the gear 39 but since the gear 39 is now free to turn on the shaft 36 it offers but slight opposition to the spring 55. When this train advances and enters the section S—T and shunts the track relay R^T the magnet 48 is deenergized as previously explained. The immediate effect of deenergizing the magnet 48 is to release the clutch member 41 from the cam 40 and to permit the clutch member 41 to move into frictional engagement with the gear 39 under the influence of spring 47. The cam 40 upon being released is at once restored to its normal position due to the counterweight 71. Engagement of the gear 39 by the clutch member 41 is effective to cause the cam 53 to be rotated counterclockwise from the position to which it had advanced along with the arm 56 back toward its normal position in opposition to the spring 55, the arm 56 following the cam 53 due to the weight of its parts. As here shown, the surface of the cam 53 is so shaped as to cause a uniform rate of movement of the arm 56, that is, for each one second operation of the cam 53 the arm 56 is moved an equal angular distance about its pivot. The parts are so proportioned that for the train traveling at the speed of 40 miles per hour the arm 56 is moved back to its normal position from the position to which it had been advanced by the cam 40 during the 15 seconds the train was advancing through the measuring section in approximately 20 seconds. Since the train traveling 40 miles per hour requires approximately 45 seconds to travel the 2640 feet between the entrance of the section S—T and the highway H, and since the arm 56 is not restored to its normal position where it closes the contact 60—61 for a period of 20 seconds, it follows that the highway crossing signals S1 and S2 are flashed to warn highway users for a period of 25 seconds before the train reaches the intersection.

Again, a train traveling 20 miles per hour consumes 30 seconds in moving through the measuring section R—S and entering the operating section S—T. The cam 40 is rotated clockwise during this 30 seconds' period and is then released and allowed to swing back to its normal posi-

tion. When this train occupies the operating section S—T the cam 53 is rotated counterclockwise in response to operation of the oscillator CT as explained for the previous train. The cams 40 and 53 are so shaped that the arm 56 is moved upward by the cam 40 during the 30 seconds the train occupies the measuring section to a position where it requires substantially 70 seconds' operation of the cam 53 before the arm 56 is restored to its normal position and the contact 60—61 is closed. Since a train of a speed of 20 miles per hour requires 90 seconds to advance the 2640 feet from the entrance of the section S—T to the highway H, it follows that 20 seconds' operation of the signals S1 and S2 is effected before the train reaches the intersection.

The curve txu of Fig. 4 illustrates the time the highway crossing signals are to be operated for the different speeds up to the maximum speed of 60 miles per hour, as arbitrarily assumed in the foregoing description. The curve trs illustrates the time consumed in the measuring section R—S by trains of different speeds and which time determines the upward movement of the arm 56. The curve tsv illustrates the time required by trains of different speeds to advance from the entrance of the operating section S—T to the intersection. The curve tsx is approximately the difference between the curve tsv and the arbitrary curve txu and illustrates the delay in setting the signals into operation after the train has passed the entrance of the section S—T to assure that the operating time of the signals before the train reaches the intersection is in accordance with the curve txu . The curve tc of Fig. 5 illustrates the relationship between the curves trs and tsx of Fig. 4 and from which curve tc the shape of the cam 40 is obtained.

From an analysis of these curves and from the foregoing description of the operation of the apparatus at train speeds of 60, 40 and 20 miles per hour, it is apparent that with the apparatus constructed in the manner described the time measuring member (arm 56) is moved upward about its pivot at a variable rate and is restored at a uniform rate, and the highway crossing signals are set into operation at least 20 seconds prior to the arrival of a train at the intersection when the speed is 20 miles per hour and the operating time is increased for the higher speeds until at the maximum speed of 60 miles per hour the signals are set into operation 30 seconds prior to the arrival of the train at the intersection. As stated hereinbefore, my invention is not limited to the specific speed limits, operating time and track layout here described. The essential thing of my invention is that a time measuring member is moved away from a normal position at one rate during a measuring period the duration of which is determined by the speed of the train, and the member is then returned to its normal position at a second rate. In the form of the invention described hereinbefore, said one rate is based upon the duration of the movement and upon a predetermined speed-time curve, and said second rate is based upon a predetermined speed-time curve, and the two rates are so proportioned that the highway crossing signals are set into operation at least a predetermined minimum interval prior to the arrival of a slow speed train at the intersection, and are set into operation a predetermined maximum interval prior to the arrival of a train traveling at the maximum speed and the operating time for trains of speeds intermediate these two speeds is made to vary

between the minimum and maximum intervals in proportion to the speed. It will be apparent, however, that the cam surfaces of the cams 40 and 53 may be shaped so that the rate of movement of arm 56 away from its normal position may be a uniform rate and the rate of movement of the arm back toward its normal position may be something other than a uniform rate should it be so desired, and warning periods of the highway crossing signal may be substantially a constant interval prior to the arrival of a train at the intersection for all train speeds rather than the variable interval described hereinbefore.

Furthermore, with apparatus constructed in the manner here disclosed, a single operating unit (oscillator CT) is effective to actuate the time measuring device in both its forward and backward movements and also to operate the highway crossing signals.

In the event a train should stop or otherwise consume an unusually long time in the measuring section R—S, the cam 40 would be rotated an unusual movement clockwise and the arm 56 would be raised to the reverse position as illustrated by the dotted lines in Fig. 1. In this reverse position of the arm 56 the contact finger 63 makes engagement with the contact finger 65. Since the magnet 48 is energized while the train occupies the section R—S and its front contact 80 is closed, current is supplied from the B terminal of the current source over a simple circuit which includes contact 80, contact 63—65 and the winding of magnet 64 and that magnet is energized and attracts the armature 62 on the arm 56 with the result that the arm 56 is retained in this raised position notwithstanding the fact that cam 40 may be rotated clockwise on past the position where it engages the cam follower 58. The spring 55 is effective to rotate the cam 53 and retain it in engagement with the cam follower 59 with the arm 56 in this reverse position, the gear 49 being in mesh with the gear 39. At such time as the train which stopped in the section R—S advances and moves into the section S—T and shunts the track relay RT, the magnet 48 is deenergized, the cam 40 is released and assumes its normal position, and the arm 56 is released by the magnet 64 and is restored to its normal position by the cam 53 in response to operation of the oscillator CT. In the event a train stops in the operating section S—T and the arm 56 is restored to its normal position, prior to the train vacating the section, further operation of the cam 53 is avoided due to the portion 70 of the gear 49.

A check circuit is provided and the normal position of the time measuring device is checked. This check circuit extends from the B battery terminal over the contact 60—61, front contact 78 of the magnet 48 and thence to a signal 79. In the event the arm 56 fails to return to its normal position for any reason and the contact 60—61 is open, or if for any reason the magnet 48 is not energized and its front contact 78 is not closed, the signal 79 is without current and assumes a stop position in the usual manner for such signals. The signal 79 set at the stop position requires all trains to approach the highway H at a restricted speed.

By making the relay RV one element of an interlocking relay, the other element of which is governed by traffic to the left of the highway H, the highway crossing signals S1 and S2 may be governed in the usual manner for trains moving

against the normal direction of traffic. The relay R^V may be provided with a back contact 81 and current supplied directly to the signal lamps through the contacts 19-20 and 21-22 during the time a train occupies the positive operating section T-V if desired.

Although I have herein shown and described only one form of apparatus embodying my invention, it is understood that various changes and modifications may be made therein within the scope of the appended claims without departing from the spirit and scope of my invention.

Having thus described my invention, what I claim is:

15. 1. In combination, a time measuring device including a ratchet gear and a circuit controlling element which element normally occupies a given position, operating means including a winding effective when energized to actuate the ratchet gear in its forward direction, a first means operated by said gear and including a first cam effective to move said element away from the given position at a variable rate, a second means operated by said gear and including a second cam effective to restore the element toward the given position at a uniform rate, and means for selectively governing said first and second means.
20. 2. In combination; a time measuring device including an oscillating armature, a ratchet gear and a circuit controlling element, said ratchet gear operated in its forward direction in step with oscillations of the armature and said element normally occupying a given position; a first control means operated by said gear and including a first cam effective to move said element away from the given position at one rate in response to oscillation of said armature, and a second control means operated by said gear and including a second cam effective to move said element toward said given position at a second rate in response to oscillation of said armature.
25. 3. Time measuring means comprising, a circuit controlling contact member biased to a normal position, an operating unit including a winding, a first cam adaptable of operation by said unit when the winding is energized and effective to move the member away from said normal position for positioning the member in accordance with the time interval said cam is operated, a second cam adaptable of operation by said unit when the winding is energized and effective to restrain movement of said member by its bias and to permit the member to gradually return to its normal position, clutch means including a clutch magnet to select said first or said second cam for operation by said unit according as the magnet is energized or is deenergized, and control means for controlling the energization of said winding and said magnet.
30. 4. Time measuring means comprising, a circuit controlling contact member normally occupying a given position, an operating unit including a winding and an armature which is oscillated at a predetermined rate when the winding is energized, a ratchet gear connected with the armature for rotation step by step in response to oscillation of the armature, a cam disposed when rotated to move said member away from said given position, said cam shaped for imparting a varied displacement to the member in accordance with the time interval the cam is rotated, means including a clutch magnet to op-

eratively connect the cam with said gear when the magnet is energized for displacing said member in accordance with the lapsed time starting from the initial energization of said winding, and means for controlling the energization of said winding and said magnet.

5. Time measuring means comprising, an operating unit including a winding and an armature which is oscillated at a predetermined rate when the winding is energized, a ratchet gear, 10 means to rotate the ratchet gear step by step in its forward direction in response to oscillation of said armature, a circuit controlling contact member, a first drive means effective to move said member in a forward direction in response to the rotation of said ratchet gear, a second drive means effective to govern the movement of said member in a backward direction in response to rotation of said ratchet gear, a clutch magnet operative to render either the first drive 20 means or the second drive means effective according as said magnet is energized or is deenergized, and control means for governing the energization of said winding and said magnet.

6. Time measuring means comprising, a circuit controlling contact member biased to a normal position, an operating unit including a winding and an armature which is oscillated at a predetermined rate when the winding is energized, a ratchet gear connected with the armature for rotation step by step in response to oscillation of the armature, a first cam disposed when operated to move said member away from said normal position for imparting a displacement to the member in accordance with the time interval the cam is operated, means including a second cam to restrain movement of said member by its bias and to permit said member when said second cam is operated to return to the normal position at a predetermined rate, clutch 35 means including a clutch magnet to connect either said first cam or said second cam with said ratchet gear for operation thereof according as said magnet is energized or is deenergized, and control means for governing the energization of 40 said winding and said magnet.

7. Time measuring means comprising, an operating unit including a winding and an armature which is oscillated at a predetermined rate when the winding is energized, a ratchet gear 50 rigidly mounted on a first shaft, means operative to rotate the ratchet gear step by step in its forward direction in response to oscillation of said armature, a first drive means including a first cam loosely mounted on said first shaft, a second drive means including a second cam rigidly mounted on a second shaft and a gear train having a drive gear loosely mounted on said first shaft and a driven gear rigidly mounted on said second shaft, clutch means including a clutch 60 magnet for selectively connecting either said first cam or said drive gear with the ratchet gear according as said magnet is energized or is deenergized, a contact controlling arm biased to a normal position and having two cam followers one engaging each of said cams for movement away from the normal position in response to rotation of said first cam and for movement back to the normal position by its bias as permitted by rotation of said second cam, and control means for governing the energization of 65 said winding and said magnet.
